UNITED STATES PATENT OFFICE.

OTTO R. BARNETT, OF GLENCOE, ILLINOIS.

ANTICREEPER.

1,248,790.

Specification of Letters Patent.

Patented Dec. 4, 1917.

Application filed June 15, 1914. Serial No. 845,162.

To all whom it may concern:

Be it known that I, OTTO R. BARNETT, a citizen of the United States, residing at Glencoe, in the county of Cook and State of Illinois, have invented certain new and useful Improvements in Anticreepers, of which the following is a specification.

My invention relates to improvements in that type of devices for preventing the creeping of railway rails, which comprises a yoke provided at opposite ends with jaws for engaging the rail base, and a key or wedge provided with a tie abutting member and adapted to clamp the jaws of the yoke 10 into gripping engagement with the rail, preferably with a spring action, and in such a manner that the tendency of the rail to creep will progressively tighten the grip of the device on the rail.

The object of my invention is to provide a device of this character of highest efficiency, maximum strength with minimum weight of material, simple of design, easy of application and securely attached to the rail 25 at all times, regardless of whether or not the tie abutment is in engagement with the tie.

A further object of my invention is to secure a maximum of efficient resiliency combined with a maximum of strength and 30 holding power. The resiliency or spring action may be provided by the yoke or by the wedge, or by both.

In the preferred form of my invention the yoke and jaws are formed integrally of a 35 single piece of metal, preferably relatively thin metal, such as sheet steel, formed up in such a manner that there is a maximum of resiliency in the direction in which resilience is desirable, and a minimum of resiliency 40 with a maximum of resistance in holding power in the direction in which the creeping strain of the rail is applied.

Another object of my invention is to provide a novel spring wedge for anti-creepers, 45 regardless of the particular form of yoke used.

Another object of my invention is to provide an automatic take-up or locking device whereby the wedge and the yoke may be 50 positively interlocked. These and such other objects as may hereafter appear, are attained by my device, certain preferred forms of which are disclosed in the accompanying drawings, in which—

Figure 1 illustrates my device with a spring yoke and spring wedge applied to

the base of the rail, the yoke and jaws being formed of one piece;

Fig. 2, an end view of Fig. 1;

Fig. 2^a, a modified arrangement of the 60 jaws of Fig. 2;

Fig. 2^b, another modification;

Fig. 3, a perspective view of the device shown in Fig. 1;

Fig. 4, a plan view of the blank for forming my improved yoke when the same is made with its jaws from a single piece of sheet metal;

Fig. 5, a plan view of a similar blank for my improved form of wedge;

Fig. 6, a perspective view of the improved form of the blank of Fig. 5;

Fig. 7, a perspective view of a modified form of sheet metal wedge;

Fig. 8, a modification of the form of 75 wedge shown in Fig. 6; and

Fig. 9, a longitudinal section on line 9—9 of Fig. 1 but with a modified form of wedge which may be the sheet metal wedge of Fig. 7, or may be a solid wedge.

Like characters of reference indicate the same parts in the several figures of the drawings.

A indicates a railway rail, B a tie or other abutment which may be engaged by the 85 apron of the wedge. C is the yoke which may be formed integrally with the jaws D, E, or separately therefrom, as shown in Fig. 2^a.

The jaws D, E are provided with flanges or gripping members d, e, which are preferably bent laterally in a direction away from the abutment B which is engaged by the wedge, the angle formed between flanges e and the jaw E on the one end and the flanges d and the jaw D on the other are 95 preferably less than the angle of the inclined upper surface of the base of the rail so that, with the flanges or gripping members d, e, bent away from the tie, as shown, and snugly engaging the upper surface of 100 the rail flange, any tendency of the rail to creep or travel in the direction indicated by the arrow will tend to swing the members d, e in the same direction, thus causing them to ride or wedge upwardly upon the lateral inclined upper surface of the rail base, thereby tightening the vertical grip of the members D, E, on the upper surface of the rail base. (Where, as in my at present preferred construction, the yoke and rail engaging 110 jaws are formed up from the blank, as shown in Fig. 4, of a single piece of rela-

80

90

105

110

tively thin resilient metal, it will be seen that, while the body of the yoke extending underneath the rail will have a maximum of vertical resiliency, tending to constantly hold the wedge and the rail engaging jaws in engagement with the rail under spring tension, this wide and thin construction of the body of the yoke permitting of suitable tempering and efficient spring action with a minimum danger of breakage), at the same time the vertical grip of the jaws or members D, E will be edgewise of the metal, thus offering a strong, rigid, locking engagement with the surface of the rail tending to cause the sharp edges of the jaws to bite into and sufficiently grip the upper edge of the rail. Furthermore, the jaws being laterally resili- 10 ent, they will tend to be moved laterally toward the tie by any longitudinal movement 20 of the rail in that direction, such lateral swinging movement of the jaws causing them to ride upon and more efficiently wedge on to the inclined upper surface of the rail as previously noted.

25 Where the yoke is made in one piece, the jaw D will have a sufficiently deep undercut to permit it to be slipped over the rail until the flange e will clear the upper edge of the rail, whereupon the flange e is slipped over 30 the rail and the rail base is seated in the yoke, as shown in Fig. 1. Either or both pairs of jaws, however, may be made separate from the portion of the yoke extending underneath the rail, as shown in Fig. 2^a, in 35 which C' indicates the strip extending underneath the rail and D' indicates a pair of jaws over which the bar or strip C' is seated and is secured against longitudinal displacement by the flange e'.

40 It will be noted that in all forms of yoke shown in the drawings, by a slight addition of metal each yoke is provided with two jaws at each end so that the breaking strain upon each anti-creeping device, because of 45 the tendency of the rail to creep, will be borne by four jaws instead of two, thus dividing the strain and increasing the strength at the needed points, since experience has shown that in anti-creepers using a 50 sheet metal yoke, a most frequent point of breakage is between the jaw and the yoke.

55 Applying my device, if it should happen that when first applied both jaws of each pair do not effectively engage the rail, the preferred arrangement of the jaws above 60 described permits of driving the non-engaging jaw in the direction indicated by the arrow until it does ride sufficiently on the tapered surface of the rail base to grip the same, but, with proper care in designing, this expedient will not be necessary. My device, as thus far described, is adaptable for use with any wedge provided with a shoulder or abutment to engage the tie. Such wedge 65 may be or may not be provided with cor-

rugations on its tapered under surface, as shown in Fig. 9, tending to engage the upper corner of the yoke beneath the rail and farthest away from the tie. The yoke being resilient, the tendency of the wedging action 70 would be to incline the yoke vertically lengthwise of the rail, as shown in Fig. 9, and thereby tip the corner mentioned into engagement with the corrugations on the under surface of the wedge. This action may 75 be facilitated, if desired, by slightly upsetting this upper corner of the yoke, as indicated in Fig. 9. Preferably, however, the wedge is formed of the single piece of sheet metal, as shown in Figs. 6, 7 and 8. The 80 wedge in Fig. 6 is formed from the blank shown in Fig. 5, the portion F forming the flat upper surface of the wedge which preferably engages the under surface of the rail base throughout its entire length, the portion G being bent at an angle to the portion F to form the apron or tie abutting portion, and the portions H being longitudinal and preferably slightly tapered flanges which are 85 curved downwardly and inwardly, as shown 90 in Fig. 6, to form resilient or spring members, the inner ends of the flanges H also engaging and bracing the apron G. With such a wedge the yoke may be non-resilient and indeed the yoke and its jaws may be 95 cast in one piece in finished form, or, as I prefer, the yoke and the wedge may both be resilient. If desired, flanges H may be slit transversely as shown in Fig. 8, and bent at 100 one or both edges of the slits out of a continuous plane, so as to provide a plurality of spring teeth adapted to spring over and engage the upper corner of the yoke underneath the base of the rail, or any projection which may be provided on the yoke, as, for 105 example, by upsetting the edge of the yoke, as shown in Fig. 9 and previously described.

Fig. 7 shows a slightly different form of sheet metal wedge in which the flanges H' are bent at an angle to the body portion F' so as to brace apron G', and are corrugated at their lower edges. In Fig. 2^a it will be noted that the jaws D are inclined at a pronounced angle transversely of the yoke C and in the direction of the length of the rail. By this arrangement the strain on the jaws D (the jaws E being arranged likewise) resulting from the tendency of the rail to 110 creep, becomes a pull edgewise of the jaws D, E, rather than transversely thereon. 115

It is obvious that various departures may be made from the exact structures shown without departing from the spirit of my invention which contemplates such changes in form. 120

I claim:

1. An anti-creep device comprising a yoke provided at each end with a plurality of rail holding jaws, means for holding same in engagement with the rail, and a tie abutting 125

130

- member, each of said jaws having substantially the same thickness in cross section as the body of the yoke.
2. An anti-creeper comprising a yoke adapted to extend underneath the rail and provided at each end with a plurality of rail gripping jaws, said yoke and jaws being formed of a single piece of sheet metal, means for holding the same in engagement with the rail, and a tie abutting member.
3. An anti-creeper consisting of a yoke provided at opposite ends with a plurality of rail gripping jaws, said yoke and jaws being formed of a single piece of resilient sheet metal, means for holding the same in engagement with the rail, and a tie abutting member.
4. An anti-creeper comprising a yoke provided at each end with a plurality of rail gripping jaws, said yoke and jaws being formed of a single piece of resilient sheet metal, the jaws being bent up laterally in opposite directions from the sides of the body of the yoke, means for holding said yoke under tension to hold said jaws in gripping engagement with the rail, and a tie abutting member.
5. An anti-creeper comprising a yoke adapted to extend beneath the base of a rail and provided at each end with a plurality of rail gripping jaws, said yoke and jaws being formed of a single piece of resilient sheet metal, and provided with a tie abutting member and arranged to be wedged between said yoke and the rail so as to hold the yoke under tension and the jaws in gripping engagement with the rail.
6. An anti-creeper comprising a yoke adapted to extend beneath the base of a rail and provided at opposite ends with a plurality of rail engaging jaws, said yoke and jaws being formed of a single piece of resilient sheet metal and said jaws being bent upwardly from the opposite edges of said yoke so as to engage the rail edgewise of the metal, and a wedge provided with a tie abutting member and adapted to wedge between the rail and the yoke so as to hold the yoke under tension and thereby hold the jaws in gripping engagement with the rail.
7. An anti-creeper comprising a relatively wide and thin resilient member adapted to extend beneath the base of a rail and provided at each end with a plurality of rail engaging jaws, means for holding said member under tension whereby said jaws are held in gripping engagement with the rail, and a tie abutting member.
8. An anti-creeper comprising a relatively wide and thin resilient member adapted to extend beneath the base of a rail and provided at opposite ends with pairs of rail engaging jaws formed of relatively wide and thin metal and arranged to grip the rail edgewise of the thickness of the metal, means for placing said resilient member under tension, and a tie abutting member.
9. An anti-creeper comprising a resilient member of relatively wide and thin metal adapted to extend underneath the rail and provided at each end with a plurality of jaws formed of relatively wide and thin resilient metal and arranged to engage the rail edgewise of the thickness of the metal, means for holding said first named member under tension whereby said jaws are held in gripping engagement with the rail, and a tie abutting member.
10. An anti-creeper comprising a resilient member adapted to extend beneath the base of a rail and provided at each end with a pair of jaws formed of relatively wide and thin metal, said jaws being provided with rail engaging flanges bent lengthwise of the rail in a direction away from the tie abutting member, means for holding said first named member under tension and said flanges in gripping engagement with the rail, and a tie abutting member.
11. An anti-creeper comprising a yoke of resilient metal adapted to extend beneath the base of a rail and provided at each end with a pair of jaws formed of relatively wide and thin metal, each of said jaws having rail engaging flanges adapted to engage the rail edgewise of the metal, said flanges being bent in a direction away from the tie abutting member, a wedge adapted to hold said yoke under tension and said flanges in gripping engagement with the rail, said wedge being provided with a tie abutting member.
12. An anti-creeper comprising a relatively wide and thin yoke of resilient metal provided at each end with a pair of jaws of similar metal, said jaws being provided with rail engaging flanges adapted to engage the rail edgewise of the metal of said jaws, a wedge adapted to be interposed between the rail and said yoke to put said yoke under tension and to hold said flanges in gripping engagement with the rail, said wedge being provided with a tie abutting member, said jaws being inclined in the direction of said tie abutting member and said flanges being bent in a direction away from said tie abutting member, substantially as described.
13. An anti-creeper comprising a yoke having a pair of jaws at each end thereof, each jaw having a rail engaging flange, a wedge adapted to be wedged between the rail and said yoke to put said yoke under tension and to hold said rail engaging flanges in gripping engagement with the rail, said wedge being provided with a tie abutting member, said yoke, jaws and flanges being formed of a single piece of relatively thin resilient metal, said jaws being bent upwardly from opposite edges of said yoke and inclined in the direction of

said tie abutting member, said flanges being bent in a direction away from said tie abutting member and being arranged to engage a rail edgewise of the metal of which said flanges are formed.

14. In an anti-creeper the combination with a wedge having a tie abutting apron, of a yoke adapted to extend beneath the rail and provided at opposite ends with rail engaging jaws, one of said members being resilient and said wedge being provided with a plurality of teeth adapted to be engaged by an edge of said yoke when the wedge is wedged between the rail and said yoke so as to resist the separation of said elements.

15. In an anti-creeper the combination with a resilient yoke provided with rail engaging jaws, of a wedge adapted to be interposed between a rail and said yoke to put said yoke under tension, said wedge and yoke being provided with co-engaging projections.

16. In an anti-creeper the combination with a resilient yoke provided with rail engaging jaws, of a resilient wedge adapted to be interposed between a rail and said yoke so as to put said yoke and the resilient parts of said wedge under tension, said yoke and wedge being provided with co-engaging projections.

17. In an anti-creeper the combination of a yoke provided with rail engaging jaws, of a wedge formed from a single piece of resilient sheet metal and provided with resilient flanges and adapted to be interposed between a rail and said yoke so as to put said flanges under tension and hold said jaws in gripping engagement with the rail.

18. In an anti-creeper the combination of a yoke provided with rail engaging jaws, of a wedge formed from a single piece of resilient sheet metal and provided with resilient flanges and adapted to be interposed between a rail and said yoke so as to put said flanges under tension and hold said jaws in gripping engagement with the rail, said flanges being formed to provide a series of resilient teeth adapted to interlock with said yoke.

19. In an anti-creeper the combination of a yoke provided with rail engaging jaws, of a wedge formed from a single piece of resilient sheet metal and provided with resilient flanges and adapted to be interposed between a rail and said yoke so as to put said flanges under tension and hold said jaws in gripping engagement with the rail, said flanges being partially severed transversely, the individual sections thus formed being bent to provide a series of resilient rack like teeth tapering toward the narrow end of said wedge.

20. An anti-creeper comprising a yoke adapted to extend under the base of a rail

and formed with two rail engaging jaws at each end, said yoke and rail engaging jaws being formed from a single piece of relatively thin resilient metal, the jaws being bent up from the opposite edges of the yoke, 70 each jaw being provided with a rail engaging flange having a rail gripping edge tapering longitudinally at an angle less than the angle of the transverse taper of the upper surface of the rail base to which the device 75 is to be applied, a wedge adapted to be interposed between the base of the rail and the body of said yoke, said wedge being formed of a single piece of relatively thin resilient metal and being provided with resilient flanges bent downwardly from the upper surface of said wedge, and with a tie abutting apron bent downwardly from the upper surface of said wedge and transversely of said flanges, said flanges serving 80 to brace said apron when subjected to strain by the tendency of the rail to creep, and said rail gripping flanges and the jaws being bent in a direction lengthwise of the rail and away from said tie engaging apron on 90 the wedge when the device is assembled on the rail.

21. The combination with a railroad rail having a base, and a stationary part of a road bed, of an anti-creeper comprising a 95 bar extending beneath the rail and provided with means to engage the top of the rail base on each side thereof, and a stop part adapted to engage said stationary part and having a wedge extending between the bottom of the rail and the top of the bar, said wedge having a top bearing face bearing against the bottom of the rail and having two separate bottom bearing faces spaced apart transversely of the rail and bearing 100 upon the top of the bar.

22. The combination with a railroad rail having a base, and a stationary part of a road bed, of an anti-creeper comprising a bar extending beneath the rail and provided 110 with means to engage the top of the rail base on each side thereof, and a stop part adapted to engage said stationary part and having a wedge extending between the bottom of the rail and the top of the bar, said 115 wedge having a top bearing face bearing against the bottom of the rail and having two separate bottom bearing faces spaced apart transversely of the rail and bearing upon the top of the bar, one element of the 120 anti-creeper being sprung from a normal condition and forcing parts of the anti-creeper against the rail in tending to resume said normal condition.

23. The combination with a railroad rail 125 having a base, and a stationary part of a road bed, of an anti-creeper comprising a bar extending beneath the rail and provided with means to engage the top of the rail base on each side thereof, and a spring element 130

inserted between the rail and the bar and sprung from a normal condition and clamping the anticreeper to the rail in tending to resume said normal condition, said spring 5 element having three separate bearing faces, two of which are spaced apart transversely of the rail and bear upon the bar, and the other of which bears against the bottom of the rail above the space between the two 10 faces which bear upon the bar, and said anti-creeper being adapted to engage said stationary part.

24. The combination with a railroad rail, and a stationary part of a road bed, of an 15 anticreeper comprising an element adapted to engage the rail, and a wedge element inserted between the first named element and the rail, one element of the anti-creeper being formed of spring metal and sprung 20 from a normal condition and forcing parts of the anti-creeper against the rail in tending to resume said normal condition, said wedge element having a stop projection cut from the body thereof and bent and extending 25 into a position adapted to prevent movement of the first named element toward the small end of the wedge, and one of said elements being adapted to engage said stationary part.

30 25. The combination with a railroad rail, and a stationary part of a roadbed, of an anti-creeper comprising an element adapted to engage the rail, and a spring wedge element inserted between the first named 35 element and the rail and sprung from a normal condition and forcing parts of the anti-creeper against the rail in tending to resume said normal condition, said wedge element having a stop projection cut from 40 the body thereof and bent and extending into a position adapted to prevent movement of the first named element toward the small end of the wedge.

26. The combination with a railroad rail 45 having a base, and a stationary part of a road bed, of an anticreeper comprising a bar extending beneath the rail and provided with means to engage the top of the rail base on each side thereof, and a stop part 50 adapted to engage said stationary part and having a wedge extending between the bot-

tom of the rail and the top of the bar, one element of the anticreeper being formed of spring metal and sprung from a normal condition and forcing parts of the anti-creeper against the rail in tending to resume said normal condition, said wedge having spaced stop projections cut from the body thereof and bent and extending into positions adapted to prevent movement of the 60 bar from different positions toward the small end of the wedge.

27. The combination with a railroad rail and a stationary part of a road bed, of an 65 anticreeper comprising an element adapted to engage the rail, a wedge element inserted between the first named element and the rail, said wedge having a spring tongue forming a stop part adapted to be sprung from normal condition and to thereafter 70 spring back into normal condition and prevent movement of the first named element toward the small end of the wedge, one of said elements being adapted to engage said stationary part.

28. An anti-creeping device for rails comprising a clamp arranged to engage the rail base, a wedge located between said rail base and clamp, whereby the latter is caused to grip said rail base and arrest the creeping 80 tendency of said rail, and a resilient projection depending from said wedge and adapted to snap behind said clamp whereby separation of said clamp and wedge is normally prevented.

29. An anti-creeping device for rails, comprising a clamp arranged to engage the rail base, a wedge located between said rail base and clamp whereby the latter is caused to grip said rail base and arrest the creeping 90 tendency of said rail, and a plurality of resilient projections located on said wedge at opposite sides of the wedging surface thereof and arranged to successively snap behind said clamp, whereby separation of said 95 clamp and said wedge is normally prevented.
